ATTORNEY

UNITED STATES PATENT OFFICE.

JAMES B. BELL, OF PELZER, SOUTH CAROLINA, ASSIGNOR TO DRAPER CORPORATION,
OF HOPEDALE, MASSACHUSETTS, A CORPORATION OF MAINE.

LOOM-TREADLE GUIDE.

Application filed December 19, 1925. Serial No. 76,390.

To all whom it may concern:

Be it known that I, JAMES B. BELL, a citizen of the United States, residing in Pelzer, in the county of Anderson and State of 5 South Carolina, have invented an Improvement in Loom-Treadle Guides, of which the following description, in connection with the accompanying drawings, is a specification, like characters on the drawings representing 10 like parts.

This invention relates to loom treadle guides for directing the movement of the treadles in a cam-operated shedding mechanism.

15 In that type of shedding mechanism wherein the heddle frames are actuated by cam-operated treadles, it is now the common practice to mount the treadles at the rear of the loom and connect the free ends of 20 the treadles to the heddles and it has also been proposed to guide the free ends of the treadles in their shed forming movements.

25 In a shedding mechanism of the cam and treadle-operated type, rolls have been mounted upon the treadles for engagement by treadle-operating cams, and in such cases the rolls, or cams, or both, are liable to become worn during use, with the result that the treadles themselves are subject to a 30 twisting action about their longitudinal axes to such an extent that at times the treadles may be broken. This is especially observable in cases where the treadles are fulcrumed at the rear of the loom by open 35 fulcrum bearings, and one of the objects of the present invention is to provide means for distributing the wear between the cams and rolls and at the open fulcrum bearings, with the result that the wear at these points 40 will be uniform throughout and consequently obviate any twisting or torsional action upon the treadles about their longitudinal axes during weaving.

45 More specifically stated, the present invention contemplates the provision of a treadle guide between the treadle actuating cams and the harness connections, which may be located closely adjacent the harness connections, and comprising in its construction a 50 guide supporting bar secured to the loom frame and extending above the treadles, and provided with a downwardly extending slotted guide frame through which the treadles project.

The invention and new combination of 55 parts will best be made clear from the following description and the accompanying drawings of one good form thereof.

In the drawings:

Fig. 1 is a perspective view showing a cam 60 and treadle actuated shedding mechanism having the present invention associated therewith;

Fig. 2 is an enlarged detail perspective view of the treadle guide; and 65

Fig. 3 is a side elevation partly in section showing the mounting of the treadles by open fulcrum bearings.

The loom frame may be of usual construction and have extending upwardly therefrom the arch supports 1, between which extends the arch 2, from which the heddle frames may be suspended. In the present instance, the arch 2 is provided with the bearings 3 in which is supported the rocker 70 4 having the upper harness connections 5 and 6 secured thereto. The harness connections 5 and 6 are connected respectively with the upper bars 7 and 8 of the two heddle frames 9 and 10, and connected to the 75 lower bar of each heddle frame is a spacer rod 11 and 12. The construction so far described may be of any usual type and is herein shown as constituting one good practical form of heddles and harness connections that may be employed with the present 80 invention.

Extending between the front and rear girths 13 and 14 are the beams 15 and 16, and to the rear one of the girths (14 as 85 shown) are secured bearings or lugs 17 supporting a stud or dead shaft 18 on which the treadles 19 are mounted for rocking movement. As shown, each of the treadles 19 has an open fulcrum bearing 20 which hooks over or rests upon the stud or dead shaft 18, and between the fulcrum bearings 90 and the ends of the treadles are the treadle rolls 21 which are engaged by the treadle actuating cams 22 mounted upon the under 95 or cam shaft 23, the construction being such that as the under or cam shaft 23 is rotated, the treadles will have imparted thereto an up and down movement. The free end portion of each treadle is provided with a series 100 of teeth 24 between which and the spacer rods 11 and 12 extend the harness connections or straps 25.

The particular feature of the present invention consists of a treadle guide more particularly shown in Fig. 2, which comprises a rod supporting bar 26 having foot portions 5 27 at each end adapted to be secured to the fore and aft extending beams 15 and 16. The treadle guide supporting bar 26 is curved upwardly, as indicated in Figs. 1 and 2, so that it may be located above the treadles 10 and extend over the tops thereof between the treadle actuating cams and harness connections.

The arched treadle guide supporting bar 26 has extending from its concave surface 15 the downwardly projecting guide frame 28, provided with openings or slots 29 through which the treadles 19 extend. In order that the treadles 19 may be properly guided in their up and down movements in the slots 20 29 and prevent unequal wear of the open fulcrum bearings and the cams or rolls 22 and 21 respectively, the slots 29 in the guide frame 28 are made to closely embrace the side portions of the treadles adjacent the 25 harness connections 25 and between such connections and the treadle actuating cams. Since the treadle guide supporting bar 26 is to extend above the tops of the treadles between the treadle actuating cams and harness 30 connections, it is curved upwardly or arched to provide for the desired amplitude of movement of the free end portions of the treadles. It is found in practice that a 35 treadle guide to properly function as herein described, should not only be secured to the loom frame, but the supporting bar itself should be disposed above the treadles with the guide frame extending downwardly therefrom, and to effect rigidity of the 40 treadle guide the arched supporting bar 26 and the guide frame 28 may be formed as a

single casting readily adapted for application to looms now in use.

It may be desirable at times to move the treadle guide to different positions between the treadle operating cams and the harness connections, especially when the character of the shed is changed as by changing the amplitude of movement given to the treadles by varying the size of the treadle operating cams, and to provide for such contingency the arched supporting bar 26 has its side supporting portions 27 slotted at 30 to receive the bolts 31 which secure the arched supporting bar to the frames 15 and 16. By loosening the nuts 32 the treadle guide may be adjusted towards or from the harness connections or towards or from the treadle actuating cams, to most effectively function in preventing torque or twisting movement of the treadle and unequal wear between the treadle actuating cams and rolls.

What is claimed is:

1. A treadle guide for looms, comprising an upwardly arched guide supporting bar having end feet provided with means for securing the supporting bar in different positions to the loom frame, and a treadle guide frame extending downwardly from the arched supporting bar and having guide openings for the treadles. 65

2. A treadle guide for looms, comprising an upwardly arched guide supporting bar having end feet for securing the supporting bar to the loom frame, and a guide frame extending from the concaved portion of the supporting bar and having guide openings. 70 75

In testimony whereof, I have signed my name to this specification.

JAMES B. BELL.
